The ornamental appearance for a segmentable slug, as shown and described.

DESCRIPTION

FIG. 1 is a perspective view of the segmentable slug in accordance with my design;

FIG. 2 is a left side elevation view of the segmentable slug as shown on FIG. 1;

FIG. 3 is a right side view elevation view thereof;

FIG. 4 is a front elevation view thereof;

FIG. 5 is a bottom plan view thereof; and,

FIG. 6 is a top plan view thereof.

The rear elevation view is not shown and does not form a part of the claimed design.
